UNITED STATES PATENT OFFICE

JOHN A. WERTZ, OF CANTON, OHIO

REFLECTOR SIGNAL

Application filed November 2, 1927. Serial No. 230,501.

My invention relates to signals as for example for warning automobile drivers of dangerous places in a roadway, and adapted for flashing warning signals by reflecting light from external sources as from the headlights of the oncoming automobiles, thereby warning the drivers of the danger in ample time to stop the automobiles or bring them under control.

Difficulties have been experienced, in connection with the use of reflector signals of this type, in providing a signal capable of reflecting light projected therein from angles, either lateral or vertical.

Difficulty has also been experienced in providing a reflector and protective case therefor, which will withstand the action of the elements; and, more particularly, because the reflectors are usually made of one material, which may be an aluminum alloy, and the cases of another material, which may be semi-steel, difficulty has been experienced in providing a reflector construction adapted to resist the alternate differential expansions and contractions of the reflector and casing.

Accordingly the objects of the present improvements include the provision of a reflector signal of high efficiency for reflecting light projected therein, and particularly adapted for reflecting light projected into the signal at relatively wide angles with the normally horizontal longitudinal axis of the reflector.

Further objects of the improvements include the provision of a construction for the reflecting signal permitting independent expansion and contraction of the reflector and protecting casing.

These and ancillary objects are attained in the improved reflector signal hereinafter set forth in detail, and which may be stated in general terms as including a case, and an improved reflector mounted in the case, the reflector and the case having only three point contact with each other, and thereby being adapted for expansion and contraction independent of each other; and the reflector including a plurality of plane reflector surfaces intersecting each other preferably at right angles to form a plurality of concave tri-

hedral angle reflectors having parallel longitudinal axes.

A preferred embodiment of the present improvements is illustrated in the accompanying drawings forming part hereof, in which

Figure 1 is a front elevation of the improved reflector signal, portions of the casing and the colored glass light transmitter being broken away to illustrate the construction of the signal;

Fig. 2, a vertical axial sectional view thereof as on line 2-2, Fig. 1;

Fig. 3, a fragmentary horizontal sectional view thereof as on line 3-3, Fig. 2;

Fig. 4, a fragmentary horizontal sectional view thereof as on line 4-4, Fig. 2;

Fig. 5, a fragmentary vertical sectional view thereof, as on line 5-5, Fig. 2; and

Fig. 6, a detached rear elevation view of a partially disassembled reflector for the signal.

Similar numerals refer to similar parts throughout the drawings.

The improved reflector signal indicated generally at 1 includes a case 2 preferably in the form of a semi-steel casting, and including a normally vertically extending rear wall 3 provided therein with an outwardly opening vertically extending T slot 4, having an open lower end 5 for receiving heads 6 of supporting bolts 7, which preferably extend horizontally from a standard 8 for supporting the signal, and the T slot having a closed upper end 9 for hanging the casing on the upper supporting bolt 7.

Trapezoidal case walls 10, 11, and 12 extend forwardly from the case rear wall 3, and the inner surfaces of the walls 10, 11, and 12 form a concave truncated trihedral angle, and the forward edges of the walls 10, 11, and 12 form a closed triangle, and flanges 10^a, 11^a, and 12^a extend outwardly respectively from the forward edges of the walls 10, 11, and 12. Forwardly extending flanges 10^b, 11^b, and 12^b project respectively from the outer edges of the outwardly extending flanges 10^a, 11^a, and 12^a.

The case 2 carries therein, an improved reflector indicated generally at 13, and which

includes a plurality of preferably plane reflecting surfaces intersecting each other preferably at right angles to form concave trihedral angle reflectors, whose apexes are at 14^a, 14^b, and 14^c, respectively.

5 While any desired number of concave trihedral angle reflectors may be provided in a suitable case, the present embodiment includes three trihedral angle reflectors, which are formed by the outer polished plane surfaces of outer trapezoidal reflector plates 15^a, 15^b, and 15^c, the side edges of which are contiguous with each other, and the planes of which are preferably perpendicular with each other, and of inner square reflector plates 16^a, 16^b, and 16^c, the planes of which are preferably perpendicular to each other and to the several intersecting planes of the outer plates; the outer plane surfaces of the square plates 16^a, 16^b, and 16^c thus being three outer intersecting plane surfaces of a cube, with their apex at 17.

10 A concave right trihedral angle reflector is thus formed by the intersecting outer plane surface of each of the following plates: 15^a, 15^b, and 16^a; 16^b, 15^b, and 15^c; and 15^a, 16^c, and 15^c.

15 The longitudinal axes through the apexes 14^a, 14^b, and 14^c of the several trihedral angle reflectors are thus parallel with each other, and with the longitudinal axis passing through the cube apex 17, which is the longitudinal axis of the reflector 13 as a whole.

20 By this arrangement of the reflecting surfaces, any light ray projected into the reflector 13 within an angle of substantially 45 degrees with the longitudinal reflector axis through the apex 17, will be reflected back towards the source of light by the action of the surfaces of the trihedral angle reflectors intersecting each other at 90 degrees, according to the well-known law that the angle of reflection from a plane reflector is equal to the angle of incidence, whereby any ray striking one of the reflector surfaces at a given angle will be reflected from that surface towards one of the other intersecting reflecting surfaces and strike the second surface at the original angle of incidence, the angle between the planes of the reflecting surfaces being 90 degrees; and consequently the ray is reflected from the second surface in a ray which is parallel with the incident ray.

25 The improved reflector 13 is secured within the casing for providing independent differential expansions and contractions of the reflector and casing, by the following means: A reflector mounting block 18 includes six walls having outer plane faces at right angles with each other and lying in the several planes of a cube. The outer surfaces of the cubical rear walls 19^a, 19^b, and 19^c of the block 18 are adapted for abutment with the outer surfaces of the smaller ends of the reflector plates 15^a, 15^b, and 15^c, respectively. Suitable apertures

20 are provided in each of the walls 19^a, 19^b, and 19^c, whereby the reflector plates 15^a, 15^b, and 15^c may be secured to the walls 19^a, 19^b, and 19^c, respectively as by means of bolts 21 passing through the apertures 20 and being provided with suitable nuts and there being 70 preferably provided a backing plate 22 between each of the reflector plates and its bolt head.

75 The front cubical walls 23^a, 23^b, and 23^c of the block 18 have outer surfaces at right angles with each other and adapted for abutment against the inner surfaces of the cube plates 16^a, 16^b, and 16^c respectively.

80 Tangs 24 on the cube plates 16^a, 16^b, and 16^c are adapted for engagement with tangs 25 on the trapezoidal plates 15^a, 15^b, and 15^c for securing the cube plates, which are preferably folded from a single sheet of material, upon the block 18, as aforesaid.

85 The front walls 23^a, 23^b, and 23^c of the block 18 merge at their forward ends in a triangular wall 26 perpendicular to the diagonal of the cube coinciding with the planes of the outer faces of the several walls 19^a, 19^b, and 19^c, 23^a, 23^b, and 23^c; this cube diagonal coinciding with the longitudinal reflector axis through the apex 17.

90 A threaded aperture 27, whose center coincides with this cube diagonal, is provided in the triangular wall 26 for receiving the threaded end 28 of a clamping screw 29 which passes through a suitable aperture 30 in the case rear wall 3.

95 Three feet 31 protrude rearwardly from the block 18 for abutment against three ribs 32 protruding outwardly from the front face of the wall 3, whereby when the threaded end 28 of the screw 30 is screwed into the threaded aperture 27 of the triangular wall 26, the head 33 of the screw abuts against the outer face of the wall 3, clamping the block 18 in place within the casing, with three point contact between the block and casing at the feet 31 and flanges 32, and the inner surfaces of the case walls 10, 11, and 12 being spaced a suitable distance from all surfaces of the reflector 13 and its mounting on the block 18; whereby the reflector 13 and case 2 may expand and contract independently of each other.

100 For coloring the signal light reflected from the reflector 13, a triangular pane 34 of wire glass preferably colored red is provided for covering the open front end of the reflector 13; and the pane 34 may be secured upon the case 2 by interposing wooden spacer strips 35 between the case flanges 10^a, 11^a, and 12^a and the inwardly extending flanges 36^a, 37^a, and 38^a of a triangular clamping frame 39.

105 120 125 Rearwardly extending flanges 36^b, 37^b, and 38^b protrude from the outer edges of the flanges 36^a, 37^a, and 38^a, respectively, for overlapping the forwardly extending case flanges 10^b, 11^b, and 12^b.

5 Bolts 40 extend through suitable apertures in the flanges 36^a, 37^a, and 38^a registered with like apertures in the flanges 10^a, 11^a and 12^a, respectively, and suitable nuts 41 for the bolts complete the means for clamping the colored glass pane 34 at the forward open end of the case 2 over the reflector 13.

I claim:

10 1. A reflector signal including a casing, a reflector mounting block secured to the casing, a reflector mounted on the mounting block within the casing, and cooperating means between the mounting block and casing permitting independent expansion and contraction of the reflector and the casing.

15 2. A reflector signal including a casing, a reflector mounting block secured to the casing, a plurality of plane reflector surfaces secured to the mounting block within the casing, and cooperating means between the mounting block and casing permitting independent expansion and contraction of the reflector surfaces and the casing.

20 3. A reflector signal including a casing, a reflector mounting block, a reflector mounted on the mounting block within the casing, a plurality of ribs on the casing, a plurality of feet on the mounting block for abutment against the ribs, and means for clamping the mounting block within the casing with the ribs and feet in engagement.

25 4. A reflector signal including a casing, a reflector mounting block secured to the casing, a plurality of plane reflector surfaces intersecting each other at right angles carried by the mounting block, and cooperating means between the mounting block and casing permitting independent expansion and contraction of the reflector surfaces and the casing.

30 40 5. A reflector signal including a casing, a reflector mounting block secured to the casing, a plurality of trihedral angular reflectors carried by the mounting block, and cooperating means between the mounting block and casing permitting independent expansion and contraction of the reflectors and the casing.

50 55 6. A reflector signal including a casing, a cubical reflector mounting block secured to the casing, three plane reflector surfaces independently mounted on three sides of the cubical mounting block, three plane reflector surfaces inclosing the remaining three sides of the mounting block, and cooperating means between the first three reflector surfaces and the last three reflector surfaces securing the last three reflector surfaces in abutment against the mounting block.

60 65 7. A reflector signal including a casing, a cubical reflector mounting block secured to the casing, and a plane reflector surface mounted on each of the outer surfaces of the said cubical mounting block and spaced from the casing.

8. A reflector signal including a relatively large concave trihedral reflector, and a relatively small convex trihedral reflector located within the concave reflector with each face of the small reflector perpendicular to two faces of the large reflector.

In testimony that I claim the above, I have hereunto subscribed my name.

JOHN A. WERTZ.
